UNITED STATES PATENT OFFICE.

MAURICE J. WOHL, OF NEW YORK, N. Y., ASSIGNOR TO M. J. WOHL & CO., INC., OF LONG ISLAND CITY, NEW YORK. A CORPORATION OF NEW YORK.

PORTABLE ARC LAMP.

Application filed January 17, 1921. Serial No. 437,987.

To all whom it may concern:

Be it known that I, MAURICE J. WOHL, a citizen of the United States, and residing at New York city, in the county of Queens and State of New York, have invented certain new and useful Improvements in Portable Arc Lamps, of which the following is a specification.

This invention relates to portable arc lamps and particularly to the multiple type of such lamps which is used for the illumination in photographic processes and which are provided with a continuous carbon feed mechanism. It is the object of the present invention to provide a lamp for photographic illumination, which is extremely light in weight and therefore may easily be carried from place to place in a studio when placed on a suitable support.

It is another object of the present invention to provide a lamp which requires little or no attention by the photographer, inasmuch as its feed mechanism works constantly and reliably without any attention.

With these and other objects in view the invention consists in a novel arrangement of the mechanism, resulting in a reduction of parts which is hereinafter fully described and finally pointed out in the claims.

In the drawings which form a part of these specifications:

Fig. I is a plan of the arc lamp partly in section on the line I—I of Fig. III; the housing is omitted in this figure.

Fig. II is a sectional elevation of the lamp on the line II—II of Fig. III.

Fig. III is a front elevation of the arc lamp mechanism without the reflector.

Fig. IV is a bottom plan of the arc lamp, from which the housing is removed.

Fig. V is a detail showing the solenoid-armature and spring suspensions.

Fig. VI is a side elevation of the upper spring suspension from which spring 43 is omitted.

Fig. VII is a side elevation of the hinged joint between the solenoid armature and connecting rod.

Fig. VIII is a diagram of the electrical connections of the lamp.

Fig. IX is a plan of spring 43 showing pins 44 and 47 in place.

Referring to Figures I to III the lamp consists of a horizontal supporting top plate 1 on which the whole lamp mechanism is

suspended by means of vertical rods. The four rods 2 hold an intermediate horizontal plate 3 on which by means of a central rod 4 a bottom plate 5 is suspended. On each of two opposite sides of plate 5 a lower carbon holder 6 with a carbon electrode 27 is held, but insulated therefrom. Plate 1 also holds by means of suspension rods 7, the resistance coils 8 preferably wound on porcelain cores and by means of rods 9 and shelf 10 the solenoid 11. At their lower ends, the rods 9 are connected by a bridge piece 12 which supports the plunger rod 13 of dash pot 14. The upper end of this dash pot is connected by means of spring suspension 15 to the laminated armature 16 of solenoid 11. The upper end of armature 16 is hinged to a forked connecting rod 17 which is joined thereto by means of pin 18. The upper end of this rod is connected to the rear end 50 of the horizontal lever 20 by a second, similar spring suspension 19. The fulcrum of lever 20 is formed in a fork 21 located at the front end of plate 1 by means of a pin 22. The rear end of lever 20 is formed by the stiff flat spring 50. Lever 20 is provided with an insulated transverse arm 23 which operates near each of its ends a clutch 25, of familiar type, by means of links 24. These clutches clamp and lift the upper carbon electrodes 26 directly when actuated by lever 20; the clutches are held in alignment with the electrode guide apertures when these electrodes are removed, by pins 32. The upper carbon connectors 28 are held only by the electrodes 26 and connected to each other by a short flexible cable 29. The electrodes 26 are guided through plate 1 by insulated plates 30 and through plate 3 by insulated plates 31. The upper and lower spring suspensions 15 and 19 are alike in construction and consist of a rigid flat bar, the ends 41 of which are bent vertically downward and provided with notches 42 (see Fig. VI) into which the ends 40 of a variable number of flat springs 43, of the shape shown in detail in Fig. IX are inserted. The extreme ends of these springs are bent, as shown in Fig. V to prevent their removal and lost motion. By means of the central pin 44, the rod 17 is rotatively connected to the springs 43 of the upper spring suspension 19. The cotter pin 47 which holds 44 in place on 17 can be bent (as shown in 110

Figs. V, VI and IX) to prevent this rotation by gripping the stationary spring 43 at either side. The lower spring suspension 15 is connected in similar manner to the dash-pot 14 but cotter pin 49 remains free to rotate with the dash-pot. The lamp mechanism is surrounded by a sheet metal housing, formed by side plates 33 and 34 provided with trunnions 37 to support the lamp in a suitable stand. Plate 35 to which a handle 36 is attached forms the back of the housing, and a reflector 38 the front of the same. The electrical connections of the lamp are shown in Fig. VIII. Current enters at the positive terminal 45, passes through one of the resistance coils 8, the solenoid 11 to the lower left carbon electrode 27 and electrode 26 forming the first arc, and directly through the flexible connection to the right carbon electrode 26, to 27 forming the second arc and to the negative terminal 46. Should the switch between A and B be closed the second resistance 8 will be connected in parallel with the first, permitting increased current to pass through the arcs. On the drawings of the lamp-mechanism the switch A—B and the wiring of the lamp are omitted. The switch is preferably detached from the lamp and the conductors leading thereto leave the lamp housing through an insulated bushing. Instead of the switch a reversible plug may be used for this purpose.

The principal innovations of this lamp mechanism are to be found in the construction which permits the separation of the operating chamber from the arcs and still permits the clutches to clamp the carbon electrodes directly, without the use of dummy rods. This is accomplished by the arrangement of lever 20. This construction also results in a great reduction of the size of the whole lamp, with a consequent reduction in weight. The electrodes of this lamp may be fed without resetting during the whole burning time of the carbons, needing no attention by the operator. Another new feature is the possibility of inserting a new pair of upper carbon electrodes into a hot lamp. It will be noticed that the upper carbon connectors in this lamp are entirely disconnected from the mechanism and serve only to connect the short cable 29 to the upper carbons and that the latter are guided only by the insulated plates 30 and 31, between which they are gripped by the clutches 25. The lower carbon electrodes can be removed by opening the screws of the lower carbon holders, they will drop out of the lamp through openings 48 of the reflector. The upper electrodes cannot fall down on the lower ones during the trimming of the lamp, because the upper carbons are never loose in any carbon holder when in the lamp. The two electrodes with their flex-

ible connection attached thereto, form the closing link for the lamp circuit and they can therefore safely be introduced into the lamp without switching the current off.

Another advantage gained by this invention is the fact that the reflector and housing need not be provided with slots for the working arms of the carbon holders through which dust always enters into the mechanism. The spring suspensions used in this lamp also embody new features and are an improvement of those shown in the Patent #1,295,271 granted to me on July 31st, 1917. The new spring attachment omits screws and nuts which may become loose by the operation of the lamp. It also permits the armature-core to be rotated about its axis to align the pin 18 parallel to arm 23 of lever 20. Pin 18 provides an axis about which rod 17 may slightly rotate and follow the circular motion of the upper spring suspension 19 which swings through an arc with lever 20.

After pin 18 is placed in parallel alignment with arm 23 the ends of pin 47 are bent upward on both sides of spring 43 of the upper suspension as shown on the drawings to make the alignment permanent.

The steadiness of the arc is greatly improved and the vibrations and consequent noise is reduced to be almost imperceptible, when the lamp is used with alternating current, since the vibrations of the core are not transmitted to the dash pot below nor to the lever above by means of the two spring suspensions. A further improvement insuring a gentle lifting of the clutches and striking of the arc is to be found in the resilient part 50 of lever 20, which will only permit the clutches to lift after the core has been lifted a definite amount, determined by the stiffness of spring 50; furthermore, as the magnetic action takes place on a longer lever arm than the lifting of the clutches, the carbon lifting-speed is decreased and the electrodes are fully heated before the opening is completed and the arc formed.

Having thus described my invention what I claim as new and desire to secure by Letters Patent is:

1. In an arc lamp of the open type a vertical plate forming part of a housing for the lamp mechanism, a pair of carbon electrodes to one side thereof, magnetic operating means on the other side thereof, a clutch on the upper electrode, a lever above said plate arranged transversely thereto to operate said clutch, one end of said lever being actuated by said magnetic means located to one side of said electrodes and a fulcrum for said lever at the other side of said electrodes.

2. In an arc lamp of the open type the combination with a top plate forming a support for an automatic operating mechanism hanging downwardly therefrom, an

inclined plate forming part of a reflector below said top plate, a carbon electrode penetrating both of these plates, a clutch on said electrode between said plates and 5 an operating lever for said clutch having its fulcrum between said plates.

3. In an arc lamp in combination, with a top plate, of magnetic means, and a reflector, both arranged below said top plate, 10 a carbon electrode extending through said top plate and into said reflector, feeding means engaging said electrode within the space formed by said top plate and said reflector and a lever to operate said feeding 15 means having its fulcrum near the open side of said reflector and its free end connected to said magnetic means.

4. In an arc lamp of the open type, two arc forming couples of carbon electrodes, 20 a housing for the lamp mechanism, means to hold one electrode of each couple in stationary position, automatic means to feed the other electrodes enclosed within said housing, and a flexible conductor connecting 25 the feeding electrodes with each other to form gripping means outside of the lamp housing to permit their free longitudinal removal from said housing.

5. In an arc lamp in combination, a pair 30 of electrodes, a clutch on one of said electrodes to lift the same, a solenoid arranged along one side of said electrode, a lever above the same joined to said clutch, an armature for said solenoid suspended from 35 said lever by means of a resilient blade held transversely to said armature and forming an expanding joint, a dash pot below said armature, a second resilient blade forming a similar expanding joint between said dash- 40 pot and armature, and a horizontally hinged connection between said armature and the resilient blade above the same arranged to bend on an axis parallel to the longitudinal axis of said blade.

45 6. In an arc lamp a solenoid, an armature

therefor, a resilient joint connected to said armature expansible in the longitudinal direction thereof, said joint comprising a resilient blade arranged transversely to said armature, a pin rotatively mounted in said 60 blade in coaxial alignment with said armature and common means to join said blade to said armature and to limit the rotative movement of said pin.

7. In an arc lamp two arc forming couples 55 of carbon electrodes, a housing for the lamp mechanism, means to hold one electrode of each couple in stationary position, automatic means to feed the other electrodes and a flexible conductor joining said feed- 60 ing electrodes with each other outside of the lamp housing, said feeding electrodes and said flexible connection forming joint means independent of any other part of the lamp, to close the lamp circuit between the arcs. 65

8. In an arc lamp a horizontal plate forming the top of a lamp housing enclosing an automatic feeding mechanism, a carbon electrode freely held in the central portion of said plate, a clutch on said electrode, an 70 operating lever therefor arranged substantially parallel to said plate in close proximity thereto, said lever having its fulcrum near one end of said plate and magnetic means to operate said lever suspended down- 75 wardly from said plate near its other end.

9. In an arc lamp a horizontal plate forming the top of a housing for the lamp mechanism, a second plate forming part of a reflector below said top plate, a pair of stationary electrodes held in said reflector, automatic feeding means within the space between said plates, a pair of movable electrodes extending through both plates and a flexible conductor joining said movable electrodes above said top plate to form gripping means for the simultaneous removal of both movable electrodes from said feeding means and from said housing. 80 85
